DESIGN FOR A PERFUME CONTAINER OR THE LIKE

Gerard Muller, New York, N. Y., assignor to Cartier, Inc., New York, N. Y., a corporation of New York

Application May 15, 1947, Serial No. 139,049

Term of patent 14 years

(Cl. D86—10)

To all whom it may concern:

Be it known that I, Gerard Muller, a citizen of the United States of America, residing at New York, in the county and State of New York, have invented a new, original, and ornamental Design for a Perfume Container or the like, of which the following is a specification, reference being had to the accompanying drawing, forming part thereof.

I claim:

The ornamental design for a perfume container or the like, as shown.

GERARD MULLER.
